DISPENSER FOR ROLLS OF FILM

William J. Burke, La Due, Mo., assignor to Roll-O-Sheets Inc., St. Louis, Mo., a corporation of Missouri

Filed Aug. 17, 1966, Ser. No. 3,493

Term of patent 14 years

(Cl. D52—2)

I claim:

The ornamental design for a dispenser for rolls of film, as shown and described.
